UNITED STATES PATENT OFFICE.

HARRY M. McCASLIN, OF ELMIRA, NEW YORK, ASSIGNOR TO AMERICAN LA FRANCE FIRE ENGINE COMPANY, OF ELMIRA, NEW YORK, A CORPORATION OF NEW YORK.

FIRE-EXTINGUISHER.

1,182,186.

Specification of Letters Patent.

Patented May 9, 1916.

Application filed February 25, 1916. Serial No. 80,425.

To all whom it may concern:

Be it known that I, HARRY M. McCASLIN, a citizen of the United States, residing at Elmira, in the county of Chemung and State 5 of New York, have invented certain new and useful Improvements in Fire-Extinguishers, of which the following is a full and clear specification.

The present invention relates to an improved acid holder for the type of fire extinguishers in which there is an alkaline solution carried by a tank and a quantity of acid carried in a separate smaller receptacle in the tank, so as to be mixed with the 15 alkaline solution for creating a gas for forcing liquid through a suitable discharge opening.

The acid holder of the present invention comprises a bottle shaped receptacle formed 20 upon opposite sides with supporting lugs which engage in oppositely inclined slots, formed in the depending arms of a yoke, which projects from the screw cap of the extinguisher. A stopper normally closing the 25 acid bottle is mounted upon the inner end of a screw stem which is threaded through a central opening in the cap. A yoke engages the screw stem above the stopper and is suitably connected with the acid bottle, 30 so that when the stopper is removed from the bottle the yoke is actuated for raising the bottle in its support and tipping it over for pouring its contents into the alkaline solution of the tank. The main advantages 35 of the improved arrangement are simplicity in construction and sureness of operation. With this type of extinguisher there is great danger of the bearing faces of the relatively movable parts corroding, so as to make it 40 difficult to move them. With the positive screw action for removing the stopper and tipping the acid bottle in its support, the action will be sure in spite of possible interference by corrosion.

45 In order that my invention may be fully understood I will first describe the same with reference to the accompanying drawings and afterward point out the novelty more particularly in the annexed claims.

50 In said drawings, Figure 1 is a side elevation, partly in section, of the improved acid bottle support; Figs. 2, 3 and 4 are views taken at right angles to Fig. 1, showing the acid bottle in three positions, which it assumes during operation.

1 is a screw head or cap, designed to be screwed into the open mouth of a cylindrical fire extinguisher tank of any suitable construction indicated by dotted lines 2. The head 1 has the usual oppositely projecting handles 3, by which it can be screwed into and out of position. A central internally threaded nipple 5 projects inwardly and outwardly from the head 1, for the reception of the threaded stem 10, carrying the operating handle 11 at its outer end and a conical stopper 12 at its inner end. The stem 10 has a threaded portion, indicated at 13, which engages the internal screw thread of the nipple 5. The packing 14 surrounds the stem 10 at the outer end of nipple 5 and is confined by the screw cap 15, threaded upon the external threads 16 of nipple 5. The stem 10 is also formed with an annular collar 17, which limits the outward movement of the stem through the threaded cap and also acts upon the yoke hereinafter referred to.

20 is a bottle supporting yoke comprising the two outwardly presented braced arms 21, connected by the cross bar 22, which is centrally perforated to fit over the inner extension of nipple 5 upon which it is rigidly secured by the threaded nut 25, engaging the external thread 26 of said inner extension of the nipple. Each of the yoke arms 21 is formed adjacent to its lower end with the oppositely inclined slots 30, 31, the slot 30 being closed while the slot 31 is open at its upper end upon one edge of the arm 21. 90

35 is the acid containing bottle formed upon opposite sides with pins or lugs 36, 37, which engage and work in the slots 30, 31 just referred to. The bottle 35 is preferably cut away slightly to form flattened faces 35^a 95 upon opposite sides near the bottom to afford proper space for the ends of the operating yoke arms. The bottle may also be cut away slightly, as shown at 35^b, to enable the operating yoke to rest compactly between the bottle and supporting arms.

40 is the operating yoke formed at its upper end with an offset lug 41 through which the stopper operating stem 10 passes. The yoke is confined upon stem 10 between the 105 stopper 12 and collar 17. The yoke 40 has two parallel arms 42 which rest normally in the cut out faces 35^b of bottle 35, the lower ends of the arms being offset slightly and perforated to receive the pins or lugs 36 of 110

the bottle, the lower ends of the arms resting upon the flattened faces 35^a of the bottle.

The device is shown in its normal closed position in Figs. 1 and 2 of the drawings. 5 When it is desired to use the extinguisher, the operator screws the stem 10 to the right with the result that the stopper 12 will be raised out of the mouth of the bottle 35 and when the stopper engages the yoke 40 cause 10 the yoke to lift the bottle 35 in the guide slots 30, 31, their opposite angular relation causing the bottle to gradually tip, as shown in Fig. 3, until it becomes overbalanced and tips completely over into the position shown in Fig. 4, with the result that the 15 acid is dumped out of the bottle into the alkaline solution.

I claim:

- 20 1. The combination with an extinguisher head carrying a bottle supporting frame, of a bottle movably mounted in said frame, a stopper closing the bottle stopper operating means and suitable means connected with the bottle and stopper operating means and adapted to first raise and then tilt the bottle in its support.
- 25 2. The combination with an extinguisher head carrying a bottle supporting frame, of a bottle movably mounted in said frame, an operating screw threaded in said head and carrying the stopper, and means operated

by said screw for raising and tilting the bottle in the frame.

3. The combination with an extinguisher head, having a bottle supporting yoke 35 frame formed with oppositely inclined slots, a bottle having lugs engaging the slots of said supporting frame, and an operating yoke connected with the bottle and adapted to raise it in its support to cause 40 it to tip over therein.

4. The combination with an extinguisher head carrying a bottle supporting yoke, said yoke having parallel arms formed with inclined slots, a bottle having oppositely presented trunnion lugs engaging said slots, and means for raising and tilting said bottle in its slotted support. 45

5. The combination with an extinguisher head carrying a bottle supporting yoke, said yoke having parallel arms formed with inclined slots a bottle having oppositely presented trunnion lugs engaging said slots, a threaded stem mounted in said head, a stopper carried by said stem and normally closing 50 said bottle, and an operating yoke engaging said stem and connected with said bottle and adapted to raise and tilt the bottle in its support when the stopper is removed. 55

HARRY M. McCASLIN.
